(57) **CLAIM**

The ornamental design for a wallet for electronic devices, as shown and described.

DESCRIPTION

FIG. 1 is a front, left side and first end perspective view of a wallet for electronic devices showing the new design, shown in a closed position;

FIG. 2 is a front, left side and first end perspective view of the wallet of FIG. 1 shown in an open position;

FIG. 3 is a left side elevation view of the wallet of FIG. 1 in the closed position;

FIG. 4 is a first end view thereof; and,

FIG. 5 is a second end view thereof.

The broken lines shown in the drawings represent portions of the wallet for electronic devices which form no part of the claimed design.

The wallet for electronic devices is shown broken away for ease of illustration, the precise length and width of the wallet for electronic devices is not claimed.
